CLAIM

We claim the ornamental design for a packaging container, as shown and described.

DESCRIPTION

FIG. 1 is a perspective view of a packaging container in a closed configuration;

FIG. 2 is another perspective view thereof in a closed configuration;

FIG. 3 is a rear view thereof in a closed configuration;

FIG. 4 is a front view thereof in a closed configuration;

FIG. 5 is a right view thereof in a closed configuration;

FIG. 6 is a left view thereof in a closed configuration;

FIG. 7 is a top view thereof in a closed configuration;

FIG. 8 is a bottom view thereof in a closed configuration;

FIG. 9 is a perspective view thereof in an open configuration;

FIG. 10 is a right view thereof in an open configuration;

FIG. 11 is a left view thereof in an open configuration;

FIG. 12 is a top view thereof in an open configuration; and,

FIG. 13 is a bottom view thereof in an open configuration.

The broken lines shown in the drawings illustrate portions of the packaging container that form no part of the claimed design.
